(57) **CLAIM**

The ornamental design for a combination adjustable desk lamp with clamp and mounted, removable remote control, as shown and described.

DESCRIPTION

FIGS. 1 and 2 are first and second perspective views, respectively, of a combination adjustable desk lamp with clamp and mounted, removable remote control showing the new design; FIGS. 3 and 4 are top and bottom views, respectively, of the combination adjustable desk lamp with clamp and mounted, removable remote control;

FIGS. 5 and 6 are right and left side views, respectively, of the combination adjustable desk lamp with clamp and mounted, removable remote control;

FIGS. 7 and 8 are front and back views, respectively, of the combination adjustable desk lamp with clamp and mounted, removable remote control;

FIGS. 9-12 are first perspective, second perspective, right side, and top views, respectively, of the combination adjustable desk lamp with clamp and mounted, removable remote control shown clamped onto a table, the table is shown in broken lines and forms no part of the claimed design;

FIGS. 13 and 14 are fragmentary enlarged first and second perspective views, respectively, of the combination adjustable desk lamp with clamp and mounted, removable remote control;

FIGS. 15 and 16 are fragmentary enlarged top and bottom views, respectively, of combination adjustable desk lamp with clamp and mounted, removable remote control;

FIGS. 17 and 18 are fragmentary enlarged right and left side views, respectively, of combination adjustable desk lamp with clamp and mounted, removable remote control;

FIGS. 19 and 20 are fragmentary enlarged front and back views, respectively, of the combination adjustable desk lamp with clamp and mounted, removable remote control;

FIGS. 21 and 22 are first perspective views of the combination adjustable desk lamp with clamp and mounted, removable remote control shown with the lamp adjusted to differing tilt angles;

FIGS. 23 and 24 are first perspective views of the combination adjustable desk lamp with clamp and mounted, removable remote control shown with the lamp adjusted to differing twist angles; and,

FIGS. 25 and 26 are first and second perspective views, respectively, of the combination adjustable desk lamp with clamp and mounted, removable remote control showing the remote control portion removed from the desk lamp and clamp.
